MAGAZINE PENCIL

John A. Harvey, South Chard, England

Application June 7, 1949, Serial No. 97,647
In Great Britain June 25, 1948

5 Claims. (Cl. 120—14.3)

1

This invention relates to magazine pencils. The object of this invention is to provide a pencil which can be adapted to hold a large number of leads of different colours or of degrees of hardness of the same colour or both. Hitherto the number of colours or different leads which can be contained in a pencil has been restricted by a form of construction which provides a separate holder or gripping device for each different lead and a radical change in design is necessary to provide a magazine pencil which contains many colours or leads and which is at the same time compact. Further as coloured leads are brittle and fragile it is essential that they should be firmly gripped not at one point only but along a substantial portion of their length and that the diameter of the leads should be as large as possible.

It has already been proposed to arrange the feed of different leads inside a hollow shell by gravity to a single gripping device through slots cut in a central tube and barrel with appropriate registration mechanism but this arrangement limits the number of leads which can be disposed on a circle of given radius whereas in the arrangement now proposed leads can be disposed on a circle with minimum clearance between each other and which, falling vertically, are brought to the chuck head without the aid of any mechanical device other than a specially shaped cell in the body of the pencil.

According to the present invention a magazine pencil is provided with at least one magazine, for a number of leads, located rotatably between first and second end members secured together by a tubular member which passes centrally through the magazine, one of the end members carrying a chuck having separate jaws each having a circular rib sliding down and up in a circular groove so inclined as to cause the jaws to separate or come together, and a chuck closing member mounted thereon, the second end member also having a passage therein for feeding a lead from a peripheral position into an axial position for passage into the chuck whilst the first end member is provided with an actuating member for a rod passing through the tube and the second end member carrying the chuck for moving the chuck, the magazine being rotatable relatively to the end members so as to bring one of the leads therein into register with the passage in the first end member.

Two or more magazines may be mounted between the end members and are rotatable independently of one another.

2

The magazine or magazines are preferably provided internally with lead positioning elements formed by scolloping the interior so that it extends only partly around the leads in order that the latter may be arranged adjacent as closely as possible one to another. Axial support is provided by the tube joining the end member.

The invention will now be described by way of example with reference to the accompanying drawings, wherein:

Fig. 1 is an elevation of a magazine pencil.

Fig. 2 is a vertical section of the magazine pencil shown in Fig. 1.

Fig. 3 is cross section on the line III—III, of

Fig. 1.

Figs. 4 and 5 are cross sections on the lines IV—IV and V—V, of Fig. 2.

As shown in the drawings a magazine pencil is provided with two magazines 1, 2 of circular cross section arranged end to end. Each magazine 1, 2 is provided with a number of compartments 9, 10. In the example shown each magazine has eight compartments. The compartments 9, 10 are arranged substantially in the manner shown in Fig. 3.

The upper end 3 of the upper magazine 1 is closed, except for a central opening 4. The upper end 3 is also provided with an upstanding boss 5 threaded externally by means of which it screws into a hollow cap 6 provided with a central opening 7 at its upper end.

The lower magazine 2 is closed at its upper end, as indicated at 8, except in one compartment 11. The magazine 2 bears at its lower end against a flange 12 of an externally threaded member 13 provided in its periphery with a longitudinal recess 14 communicating with an opening 15 in the flange 12.

In the member 13 is secured centrally the lower end of a tube 16 which passes axially and freely through central longitudinal bores 17, 18 in the magazines 1, 2. At the upper end of the tube 16 is a boss 19 which is provided with a diametrical saw cut 20 to facilitate the turning thereof by a suitable tool.

On the member 13 is screwed one end of a tubular member 21 in which is slidably mounted a metal member 22.

In the member 22 is provided a lead passage 23 shaped as shown but of a width only slightly exceeding the diameter of the lead of which the inlet 27 is located laterally of the longitudinal axis 25 of the member 22, while its outlet 26 is located axially of the member 22.

On the lower end of the member 22 is screwed

a ring 27 of spring metal which is provided with slits 28 and of which the lower end is turned inwardly as indicated at 29.

Into the lower end of the member 21 is screwed a conically bored metal member 30 provided on its inner surface with three circular grooves 31.

In the conically bored member 30 is mounted a lead chuck which consists of three members 32, 33, 34 each of which is provided with a circular projecting rib 35, the ribs 35 each sliding in one of the grooves 31, the upper end of each chuck member 32, 33, 34 has a hooked member 36 which rests upon the flange 29. The circular ribs 35, as they move down or up the inclined circular grooves 35 cause the chuck members 32, 33, 34 to move apart or come together.

In the cap 6 is slidably mounted an actuating member 37 which projects slightly therefrom. The actuating member is secured to the upper end of a rod 38 which passes freely through the tube 16. At its lower end the rod 38 is screw threaded and engages with a threaded boss 39 on the member 22.

The boss 39 fits into a recess in the flanged member 12, 13. In order to prevent relative turning movement between the member 22 and the tubular member 21, the member 22 is provided with a lateral projection 40 which engages with a longitudinal recess 41 in the inner surface of the member 21.

A coiled return spring 48 is coiled around the rod 38 between the actuating member 37 and the closed end of the magazine 1.

The compartments 9, 10 of the magazines 1, 2, which are held axially in position by the tube 16 are each adapted to receive a lead 42, 43. No lead is placed into the compartment 11 of the magazine 2.

When the pencil is provided with a single magazine such as 1, all the compartments 10 are closed at the upper end.

The compartment 11 in the magazine 2 provides a transit chamber to enable a lead from the magazine 1 to pass through magazine 2 into the passage 23.

The magazines 1, 2 are rotatable on the tube 16 and are preferably made of transparent material showing the colour, number and lengths of leads available.

The magazines 1, 2 may be provided on the outside with markings indicating the particular leads or colours thereof and are adapted to be brought into register with a fixed mark on the flange 12 or on the outside of a fixed portion of the pencil.

The magazine 2 may be omitted in which case the tube 16 and rod 38 are shortened or the magazine 1 and the parts 21 and 22 suitably lengthened to take longer leads.

If desired one or more additional magazines similar to 2 may be provided, the tube 16 and rod 38 being then correspondingly lengthened, whilst one compartment similar to the compartment 11, in each additional magazine is left free as a transit tube so that when they are brought into register a lead from the uppermost magazine 1 can be allowed to drop through them to the passage 23 in the member 22.

For the purpose of feeding a lead to the chuck 32, 33, 34, the particular lead is first selected and assuming this is in magazine 2, the latter is turned so as to bring this lead opposite opening 15, recess 14 and the inlet 24 into the passage 23. When the pencil is held substantially vertically, the lead then drops under the action of

gravity into the passage 23 and passes to the top of the chuck 32, 33, 34. The actuating member 37 is then pushed inwardly as a result of which the rod 38 pushes downwardly the chuck 32, 33, 34. The circular grooves 35 thus expand the jaws 32, 33, 34 of the chuck so as to enable the lead to pass into the chuck. When the lead projects the required distance from the chuck the actuating member 37 is released whereby the spring 48 returns the member 22 to its normal position, whereby the chuck is drawn into the member 30 so that it is caused to grip the lead 50 firmly.

For advancing the lead the member 37 is again pressed so as to release the lead 50.

For returning the lead 50 to its magazine the pencil is turned upside down and after the magazine 2 has been set in the required position, should it have been turned intentionally or accidentally, the actuating knob 37 is pushed inwardly so as to open the chuck and to allow the lead 50 to return to its position or compartment in the magazine.

When however a lead is to be passed from magazine 1 to the chuck, the magazine 2 is first turned so as to bring the empty compartment 11 (transit chamber) into alignment with the inlet 24 whilst magazine 1 is turned into such a position that the required lead is in alignment with the empty compartment 11 (transit chamber) in magazine 2 thus connecting the required space or compartment in magazine 1 with the inlet 24. After the pencil has been brought substantially into a vertical position the member 37 is then pressed as above described so as to enable the lead to fall by gravity into the chuck when the operations above described are carried out. For returning the lead to its compartment the operations are similar to those above described except that the empty compartment 11 (transit chamber) of magazine 2 must be brought into register with the inlet 24 and the required compartment of magazine 1 should there have been any displacement of these parts while the pencil is in use.

I claim:

1. A magazine pencil wherein at least one magazine, for a number of leads, is located rotatably between first and second end members 50 secured together by tubular member which passes centrally through the magazine, one of the end members carrying a chuck, of which the jaws are normally urged outwardly by mechanical action, and a chuck closing member mounted thereon, the second end member also having a passage therein for guiding a lead from a peripheral position into an axial position for passage into the chuck, while the first end member is provided with an actuating member for a rod 60 passing through the tube and the second end member for moving the chuck, the magazine being rotatable relatively to the end members so as to bring one of the leads therein into register with the first end member.

2. A magazine pencil according to claim 1, wherein more than one magazine are mounted end to end between the end members and are rotatable independently of one another.

3. A magazine pencil according to claim 2, 70 wherein the magazines are provided internally with lead receiving compartments, the magazine furthest removed from the chuck having its end remote from the chuck closed, the remaining magazines having one compartment therein open at both ends.

4. A magazine pencil according to claim 1, wherein the chuck is composed of a number of elements of which the upper hooked ends rest upon the interior of a spring ring secured to the chuck actuating member, the jaws of the chuck being guided by circular ribs engaging with circular grooves in a conically bored member.

5. A magazine pencil according to claim 1 wherein the passage is shaped to bring the lead from a peripheral position lateral of the longitudinal axis of the pencil to an axial position by gravity when the pencil is in one position and to move the lead from an axial position to a lateral

position under the action of gravity when the pencil is turned upside down.
